WASHING FLUID INJECTOR

Harold B. Ray, Chicago, Ill.

Application March 18, 1940, Serial No. 324,569

6 Claims. (Cl. 299—84)

This invention has as its principal object the provision of a method and improved means for injecting a washing fluid into the wash water of a dish washing or analogous machine.

A further object is the provision of a means for measuring or metering a predetermined quantity of concentrated washing fluid into the wash water of a machine of the class described by by-passing portions of rinsing water into certain metering and injecting mechanism.

A further object is the combination with a washing machine including a reservoir for wash water and a water intake supplying rinsing water, of washing fluid injecting means including a concentrating tank which provides a source of saturated alkaline washing fluid, a feed line for delivering washing fluid to the wash water, a siphon metering tank through which predetermined or measured quantities of water may be by-passed from the water supply line and delivered partly into the concentrating tank and partly into the feed line, together with means for transferring measured quantities of concentrate from the concentrating tank into the feed line as a result of the by-passing of water from the supply line.

Still another object is the provision of an improved concentrating means including a tank having a conical foraminous receptacle adapted to receive an alkaline or other washing compound for dilution in water contained in the tank, means for introducing water into the tank in the region of the apex of the conical receptacle so that the less readily soluble portions of the compound will have water actively circulated thereabout, and sloped wall portions in the tank for returning excess washing compound to the region of inflowing water when the solution is supersaturated.

Yet another object is the arrangement of injecting means so that the concentrated washing fluid will be introduced in relatively small quantities into a feeding or injecting line leading to the washing machine and relatively larger quantities of diluting wash water will thereafter be fed through the injecting line to flush the same and reduce troubles due to corrosion, crust formation and the like.

A still further object is the provision of means for bringing together saturated washing liquid and diluting water in predetermined quantities for admixture prior to or substantially simultaneously with the passage thereof into the main feeding or injecting line leading into the washing machine.

Other objects and advantages of the invention relate to certain details of the method as well as

the construction realized by the practice thereof, as exemplified in the annexed drawings, taken in view of the specification, and in which:

Fig. 1 is a vertical section through a dish washing machine employing the improved injecting means shown in elevation;

Fig. 2 is a vertical section of the injecting means of Fig. 1;

Fig. 3 is a top plan view of the concentrating tank;

Fig. 4 is a vertical elevation of the regulating valves;

Fig. 5 is a vertical section through a modified injecting device; and

Fig. 6 is a vertical section through an alarm arrangement for use with the injecting mechanism.

The invention is illustrated herein in conjunction with a known type of dish washing machine shown in Fig. 1 and including an upstanding tank 10 having a reservoir 11 in its lower region to contain a quantity 12 of washing water in which there is mixed a predetermined quantity of a washing fluid usually a strong alkali.

In the upper region of the housing 10 there is provided a means 13 for racking dishes to be sprayed by the washing fluid issued from whirling sprays 14 fed with washing fluid from the reservoir 11 by action of a pump 15. The washing liquid after being sprayed forcibly over the dishes as aforesaid, gravitates back through a strainer 16 into the reservoir 11 in which the level of the liquid 12 is maintained constant by action of an overflow duct 17 leading to a drainage gutter.

When the dishes have been sprayed with the washing liquid a sufficient time, pump 15 is stopped and a crank 18 is manipulated to operate a multiple valve 19 which cuts off the force feed line from pump 15 and admits hot rinsing water from a supply line 20 for passage through a duct 21 into lower and upper rinsing sprays 22. The rinsing water from the supply line is clear and gravitates into reservoir 11 to dilute the washing liquid 12, the dilution occurring most rapidly in the upper part of tank 10 so that weaker portions of the washing mixture are the first to be drained off through the overflow duct 17.

It will be apparent that the washing liquid 12 would soon be too dilute for effective use as a result of the repeated influx of clear rinsing water, and various expediencies have been resorted to heretofore for the purpose of strengthening or restoring the proper concentration of alkalinity to the body of the washing liquid 12.

In accordance with the method and means of the present invention, a portion of the clear rinsing water is by-passed into a measuring device which cooperates with a tank containing saturated washing liquid which is automatically transferred into the reservoir in the washing machine following each rinsing operation.

Referring to Fig. 2, the improved injecting apparatus includes a measuring device in the preferred form of an elevated tank 25 into the upper region of which is introduced clear rinsing water through a pipe 26 connected through a regulating valve 27 and a pipe 28 (Fig. 1) to the multiple valve 19. Within the metering device is a siphon 29 leading through the bottom thereof and provided with a breather 30 to prevent air locks. The arrangement is such that when the water level in tank 25 passes above the bend in the siphon 29, the incoming clear water will be delivered into a pipe 31 discharging as at 32 into an injecting or feeding line or pipe 33 (Fig. 1 also) discharging as at 34 into the bottom region of the reservoir 11 in the washing machine.

A portion of the metered clear water is bypassed from the measuring device 25 through a regulating valve 35 and a duct 36 into the bottom region of a concentrating tank 37 which contains a quantity 38 of saturated washing fluid which is maintained in its condition of saturation by the presence of a supply of the washing chemical 39 in a conical foraminous container 40.

The foraminous container 40 is preferably constructed of a suitable metal screening of relatively fine mesh, the apex 41 of the cone being situated opposite the discharge end of pipe 36, the upper end or base portion of the cone being rigidly attached to a mounting frame 42 which is provided with opposite horizontal flange portions 43 (Fig. 3) adapted to engage the upper edge portions of the concentrating tank.

The washing chemical or compound 39 is usually of a granular or lumpy consistency and dissolves in the body of the liquid 38 through the openings in the cone in proportion as the concentrated liquid is diluted by by-passed portions of clear water entering from pipe 36.

One of the purposes of the conical receptacle is to cause the heavier and sometimes less readily soluble lumps or portions of the washing chemical 39 to gravitate toward the bottom or apex 41 of the cone where the movement of diluting liquid is most active, being close to and approximately opposite the point of efflux of clear water from the lower end of pipe 36.

It will be apparent that the foregoing arrangement in the concentrating tank provides a means which affords a supply of saturated or concentrated washing liquid. Small portions of the concentrate must be delivered or injected periodically into the more dilute supply in the main reservoir 11 and to this end there is provided means for automatically transferring measured amounts of the concentrate into the intake or feeding line 33, this means including the provision of a baffle or weir 45 (Fig. 3) extending in a direction crosswise of the tank 37 at the end thereof opposite the cone and forming a small measuring compartment 46, the bottom of which is a downwardly pitched apron 47 directed toward the bottom or apex 41 of the foraminous cone. The purpose of the pitched floor or apron 47, it may be observed, is to direct any of the solute which may settle out of the concentrated

liquid back toward the region beneath the apex 41 for re-solution by the incoming clear water.

The injecting means is completed by the provision of a siphon 48 connected as at 49 to the downwardly leading portion of the supply pipe 31 so as to siphon off a certain quantity of the concentrate in chamber 46 and deliver the same into the supply line 31 for admixture with the relatively greater volume of incoming clear water from the measuring device 25, the amount of concentrate which is injected depending upon the size and elevation of the siphon 48 with respect to the other parts of the concentrating tank.

In the operation of the device of Fig. 2, referring conveniently to Fig. 1, there is normally a quantity 38 of concentrated washing solution in the concentrating tank 37, and when the operator manipulates valve handle 18 to start the rinsing operation, part of the clear rinsing water is bypassed through pipe 28 into the measuring device 25. A relatively short period of time (e. g. 10-30 seconds) must elapse before the metering tank 35 is filled to a level sufficient to start the operation of siphon 29. This period corresponds to the time during which the dishes are to be rinsed and it may be regulated by properly setting the valve 27 which controls the flow through the pipe 28, this valve, as shown in Fig. 4, being preferably provided with a scale 27a calibrated to designate desired rinsing periods.

As soon as the siphon begins to operate in the metering device 25 the attendant will observe the passage of liquid from the discharge end 32 of the clear water pipe 31 into the funneled mouth 33a of the injection or feeding line and he will thus be apprised of the fact that the rinsing period is ended whereupon the valve means 18-19 will be operated to shut off the rinsing water.

Meanwhile a relatively small portion of the clear water in the metering tank 25 will be bypassed through regulating valve 35 into the concentrating tank 37 and the liquid level will rise and spill over the weir 45 into the measuring chamber 46, there being a further short lapse of time before the liquid level in chamber 46 rises high enough to cause operation of siphon 48 to direct the operation of the concentrate through the connection 49 for admixture with the clear water in pipe 31. Valve 35 is also provided with a calibrated scale 35a to facilitate regulation of the amount of clear water bypassed into the concentrating tank, which amount is always less than the amount passing around the tank through the supply pipe 31, in consequence of which the concentrated wash liquid is washed out of the lower portions of pipe 31 and the intake or injecting pipe or line 33 so that these latter parts need not be constructed of the relatively more expensive corrosion-resistant metals of which the concentrating tank 37 and associated parts must be made, the injecting line in this respect being self-flushing.

As seen in Fig. 1, the replenishing inflow of fresh washing liquid discharges from the lower end 34 of the injection pipe close to the bottom of the reservoir 11 so that the relatively uncontaminated liquid has a chance to mix into the main body of washing liquid 12, this mixing being further facilitated by convection currents set up in the liquid by a heating device H beneath the reservoir.

In the modified arrangement shown in Fig. 5 the injecting mechanism takes the form of a combination concentrating and mixing tank in-

cluding a chamber 50 separated by a crosswise baffle or weir 51 from a mixing chamber 52. The usual concentrated liquid is maintained to the top of the weir in chamber 50 by use of a cone 40' similar to the device 40 of Fig. 2 and containing a supply of alkaline or other washing chemical in granular or subdivided form deposited directly into the cone or contained in suitable bags. As in the case of Fig. 2, the apex 53 of the cone is situated near the bottom of the chamber and closely opposite the discharge end 54 of a by-pass duct 55 connected through a regulating valve 56 to a rinsing water supply line 57 which may in turn be connected through another regulating valve 58 to the multiple water control valve 19 as in the arrangement of Fig. 1.

In the device of Fig. 5, the metering means is self-contained in that the inflowing water flowing into the concentrating chamber 50 must rise to spill over the weir into the mixing chamber 52 for admixture with the main body of clear water which is by-passed around the concentrating tank from pipe 57 through a supply pipe 59. The proportion of concentrate to clear water is regulated by manipulation of valves 56-58 and when the mixture has risen to a suitable level it is carried off automatically by a siphon 60 which discharges as at 61 into the funneled mouth 33a of the injection line 33 as in the case of the arrangement of Fig. 2, and as soon as the attendant observes the passage of liquid from the mouth 61 he is thereby given an indication that the rinsing period is over. The difference between the arrangement of Figs. 2 and 5 is pointed out in that the device of Fig. 5 is a forced feed system both with respect to the concentrating chamber 50 and the mixing chamber 52, this latter arrangement being especially suitable for larger installations wherein it is necessary to handle larger volumes of washing liquid in short periods of time and where the pressure from the water supply line does not vary enough to throw off the timing action objectionably.

In Fig. 6 there is shown an alarm mechanism to replace the visual indication given the attendant by the passage of liquid into the mouth 33a of the injection line, and this mechanism including the provision of an auxiliary float tank 70 mounted beneath the mixing chamber 52 of the device of Fig. 5 for example (or chamber 46 in the device of Fig. 2), and adapted to receive the concentrate through a siphon 71 so as to raise a float 72 to displace a switch operating arm 73 and close a switch 74 in an energizing circuit for a signaling device such as the bell 75, the concentrate flowing into the injection line 33 from the auxiliary chamber. Thus, as soon as the measured quantity of injection liquid begins to rise in chamber 70 the bell will ring to indicate the completion of the rinsing period.

It is contemplated that the injection apparatus may be employed with the type of dish washing machines which include separate washing and rinsing compartments or units. In such a case, it will be apparent that there will be no clear rinsing water mixed with the washing liquid in the washing unit and the injection apparatus will of necessity have to be connected to the rinsing supply line in the rinsing unit and the injection line be connected to the reservoir in the washing unit.

The various advantages and objects of the invention may be accomplished by modifications of the particular method and embodiment specifically described herein, and it is intended

that the appended claims shall include all equivalent arrangements fairly coming within their call.

Having thus described my invention, what I claim as new and desire to protect by Letters Patent is:

1. In a device of the class described, injecting means including a concentrating tank adapted to contain a certain volume of washing liquid, means in said tank for maintaining a supply of washing substance to be dissolved in said liquid for maintaining a desired concentration thereof, a metering tank positioned above said concentrating tank, means for by-passing quantities of water into said concentrating tank from said metering tank when the water level in the latter has reached a given height, means for diverting water from the metering tank into a delivery line, and means for siphoning a given quantity of concentrate from said concentrating tank into said delivery line.

2. In a device of the class described, injecting means including a concentrating tank adapted to contain a certain volume of washing liquid, means in said tank for maintaining a supply of washing substance to be dissolved in said liquid for maintaining a desired concentration thereof, a metering tank positioned above said concentrating tank, means for by-passing quantities of water into said concentrating tank from said metering tank when the water level in the latter has reached a given height, means for diverting water from the metering tank into a delivery line, means controlled by the change in liquid level in the concentrating tank and resulting from the admission thereto of by-passed water, for siphoning a given quantity of concentrate from said concentrating tank into said delivery line.

3. In a device of the class described, a combination concentrating and measuring device including a tank, means providing a weir dividing said tank into a concentrating chamber and a mixing chamber, means for flowing a liquid into said concentrating chamber, said liquid overflowing into the mixing chamber when more than a predetermined volume of liquid flows into the concentrating chamber, means for maintaining a quantity of chemical to be dissolved in said liquid in the concentrating chamber, means by-passing portions of said liquid past said concentrating chamber into said mixing chamber, and a siphon arranged in said mixing chamber to siphon off predetermined amounts of a mixture of the overflowed concentrate and the by-passed liquid.

4. A combination concentrating and measuring device including a tank, means dividing said tank into two chambers and providing for liquid overflow from the first chamber into the second chamber, means for introducing a liquid into said first chamber and siphon means in said second chamber to siphon off predetermined amounts of liquid overflowed into the second chamber as aforesaid providing a predetermined volume of liquid be overflowed from the first chamber to start the siphon.

5. A combination concentrating and measuring device including a tank, means dividing said tank into two chambers and providing for liquid overflow from the first chamber into the second chamber, means for introducing a liquid into said first chamber and siphon means in said second chamber to siphon off predetermined amounts of liquid overflowed into the second chamber as

aforesaid providing a predetermined volume of liquid be overflowed from the first chamber to start the siphon, together with a siphon measuring device adapted for connection with a source of liquid supply and connected for operation to transfer a predetermined volume of liquid into said first chamber when the liquid level in said device reaches a certain level from said source of supply.

6. In an injecting device, the combination of 10 a concentrating tank adapted to contain a solution, means containing a supply of solute in said solution to maintain a saturated condition therein, a siphon tank adapted for connection with a source of solvent supply and arranged 15

5 to deliver solvent therefrom to said concentrating tank by siphon action when a predetermined volume of solvent is introduced into said siphon tank, and siphon means operatively associated with said concentrating tank for leading off from the latter predetermined quantities of the concentrate responsive to certain changes in the liquid level in the concentrating tank effected by operation of the siphon means in said siphon tank, and means for mixing the concentrate led off as aforesaid with quantities of solvent from said source of supply, and means for adjusting the volumetric ratio between the amount of solvent and concentrate to be mixed as aforesaid.

HAROLD B. RAY.
